MACHINE FOR RIFLING GUN BARRELS

John E. Lovely, Springfield, Vt., assignor, by
mesne assignments, to United States of
America

Application August 11, 1943, Serial No. 498,186

12 Claims. (Cl. 90—28.1)

1

The present invention relates to a machine for rifling the bore of gun barrels.

It is the principal object of my invention to provide a machine for rifling the bore of a gun barrel having a bore which may vary in form or 5 diameter such as a taper bore gun.

In recent years, high velocity gun development has resulted in the design of a gun barrel having a bore including a taper portion to reduce the diameter of the bore from a greater diameter 10 adjacent to the chamber of the gun to a lesser diameter at the muzzle end of the gun. The projectiles to be fired in a gun of this type are known as deformable projectiles and are provided with fins or the like to fit the bore of the gun at its greater diameter adjacent to the firing chamber. These fins present a large area to the expanding gas pressure from the exploding charge in the firing chamber but during the passage of the projectile through the taper in the bore, they are 15 folded back or deformed resulting in a projectile of a reduced size diameter commensurate with the smaller diameter of the taper bore at its muzzle end. Thus the projectile of comparatively small cross section has imparted thereto a high muzzle velocity due to the initial large area exposed to the expanding gas pressure. The taper portions of the bores of gun barrels of this type have assumed various forms in development and may or may not be rifled. It is believed advantageous to rifle the taper portion of the bore and so far as I am aware, no successful rifling machines have heretofore been designed or produced which could rifle the taper portion of the bore in a manner satisfactory for economical production. 25

It is, therefore, an important object of my invention to provide a method and apparatus for rifling any or all portions of the bore of a gun barrel having a taper portion in the bore, which method and apparatus will speedily and economically produce the desired results satisfactorily from the point of view of mass production.

The method of my invention requires that the gun barrel be held in a stationary position while a cutter or broach assembly is moved in a spiral path through the bore of the gun in cutting relation with the surface of the bore to thereby machine a rifle groove having the required twist or number of turns. The cutter is given the spiral path and is maintained in accurate cutting relation with the bore by means of a cylindrical bar having a profile corresponding in form to the bore of the gun which may include a portion of varied form or diameter such as a taper. The cylindrical bar, which I term a rifling bar, is 55

2

provided with a spiral groove in which the cutter or broach assembly is moved, and the groove is of a uniform depth which will maintain the cutter during its spiral path through the tapered bore in the desired cutting relation so that a cut of uniform depth will be made. This cutting relation is maintained the same during the entire passage of the cutter or broach assembly through the bore.

It is an object of my invention to provide a rifling machine having means to support a gun barrel in a stationary position during the machining of a rifle groove together with means for rotating the barrel and indexing the barrel to a new stationary position for machining the succeeding rifling grooves.

It may be necessary that the cutter or broach assembly be passed through the bore several times in a cutting relation to the surface of the bore in order to produce a rifle groove of the required depth. It is a further object, therefore, of my invention to provide a cutter or broach assembly adapted to be passed through a spiral path in cutting relation to a gun bore of varying form or diameter and having means to adjust the cutter after each passage through the bore to effect an increase in the depth of cut or to withdraw the cutter from cutting relation with the bore.

It is also an object of my invention to provide a cutter or broach assembly as described above which is equipped with two cutters faced in opposite directions and which may be alternately engaged in cutting relation with the bore so that a cut may be effected by travel of the broach in each direction through the bore.

Further objects and advantages of my invention will be apparent by reference to the following specification and drawings in which

Figure 1 is a side elevation of the complete rifling machine of my invention showing a gun barrel in position for rifling.

Figure 2 is a plan view of machine shown in Figure 1.

Figure 3 is a plan view of the rifling bar showing the spiral groove in the surface of the bar.

Figure 4 is a detail sectional view on line 4—4 of Figure 1.

Figures 5 and 6 are detail sectional views on lines 5—5 and 6—6, respectively, of Figure 3.

Figure 7 is a longitudinal section of a portion of the rifling bar and showing a single cutter broach assembly in longitudinal section slidably positioned within the groove of the rifling bar and moving in cutting direction.

Figure 8 is similar to a portion of Figure 7, but showing the position of the cutter on the return stroke.

Figure 9 is a fragmentary view similar to a portion of Figures 7 and 8 but showing the relative positions of the parts in which the cutter can be removed or replaced.

Figure 10 is a detail sectional view on line 10-10 of Figure 7.

Figure 11 is a detail sectional view on line 11-11 of Figure 9.

Figure 12 is an exploded perspective view of certain parts of the cutting broach assembly.

Figure 13 is an enlarged detail longitudinal sectional view taken on line 13-13 of Figure 1, showing the cutting adjusting mechanism in position on the machine at the end of the rifling bar support adjacent to the breech end of the gun barrel.

Figure 14 is a detail sectional view on line 14-14 of Figure 13.

Figure 15 is an enlarged detail sectional view taken on line 15-15 of Figure 1, and showing the mechanism for indexing the gun barrel.

Figure 16 is a detail sectional view on line 16-16 of Figure 15.

Figure 17 is a view similar to a portion of Figure 7 but showing the double cutter broach assembly.

Figure 18 is a detail sectional view on line 18-18 of Figure 17.

Figure 19 is an exploded perspective view showing cooperating parts of the cutter adjusting mechanism and the cutter assembly at one end of the cutter bar.

Referring to Figures 1 and 2 of the drawings, the rifling machine is comprised of the elongated bed 1 having on its upper surface the bed rails 2 and 3. Mounted on one end of the bed 1 as shown, is a hydraulic cylinder 4 provided with the cylinder heads 5 and 6 located at each end of the cylinder. Any suitable hydraulic mechanism (not shown) comprising pump, valves and piping for distributing fluid under pressure to each end of the cylinder is provided. Slidable through the cylinder head 6 is a piston rod 7 connected to the piston 8 within the cylinder 4. By selectively supplying fluid under pressure to either end of the cylinder, the piston and piston rod will be reciprocated as should be well understood. Straddling the bed rails 2 and 3 and secured in a relatively fixed position, as shown, are the sheave supports 9 and 10. Rotatably mounted on the supports 9 and 10 are the sheaves or pulleys 11 and 12. The position of the sheave support 10 may be adjusted longitudinally of the bed 1 by means of the screw shaft 13 to which is keyed the hand wheel 14. Looped around the sheaves 11 and 12 is the wire cable 15, the ends of which are joined together by the turn buckle 16. By adjusting the turn buckle 16, or adjusting the position of the sheave support 10 by means of the hand wheel 14, tension of the cable 15 may be regulated.

The free end of the piston rod 7 is attached to a cable carriage 17 slidably positioned on the bed rails 2 and 3. It should be apparent that when the piston rod 7 is reciprocated, the cable carriage 17 will likewise be reciprocated. The cable carriage 17 is connected to one side of the looped cable 15 by means of the cable bushing 18 and shear pin 19 (see also Figure 4). Should the cable 15 resist movement by a force beyond a predetermined amount, the shear pin 19 will break, enabling the cable carriage 17 to move 75

in response to the piston rod 7 without moving the cable 15, thus protecting the cable against breakage and insuring the safety of the operator of the machine.

Still referring to Figures 1 and 2 of the drawings, the heads 20 and 21 are supported on the bed rails of the machine and are fixed by set screws or bolts in the semi-permanent positions as shown. Rotatively journaled in the heads 20 and 21 are the gun barrel receiving spindles 22 and 23. Figure 15 of the drawings is a sectional view to a larger scale clearly showing the head 20 and spindle 22 and the method of securing the spindle within the head by means of the threaded ring or nut 24. The spindle 23 is similarly retained in its head 21 by means of threaded ring 25. Bolted to the spindles 22 and 23 are the gun barrel chucks 26 and 27. Thus a gun barrel such as shown by 28 in Figures 1 and 2 may be passed through the spindles 20 and 21 and chucked in the jaws of the chucks 26 and 27.

With the gun barrel positioned through the spindles 20 and 21, and secured by the chucks 26 and 27, it should be evident that the gun barrel will be rotatively supported over the bed of the machine. To secure the gun barrel against rotation during the cutting operation, an indexing and locking device is provided as shown by Figures 1 and 2 but more clearly shown by Figures 15 and 16. To the spindle 22 is keyed a dial or index plate 29, provided with a series of appropriately spaced radial grooves 30. Pivotally mounted on the bushing 20 is an indexing lever 31 operatively connected to the push rod 32 and having a handle 33. Compression spring 34 normally urges the push rod 32 into engagement with one of the radial grooves 30 of the index plate 29 thus locking the index plate 29 and gun barrel spindle 22, together with the barrel chuck 26 and gun barrel 28, against rotation. By manipulating the handle 33, the gun barrel may be released and then manually rotated and indexed to the next station or position for cutting another rifling groove in the barrel. If, for example, the gun barrel is to have twelve rifle grooves, the index plate 29 will be provided with twelve equally spaced radial grooves 30 thus giving twelve different and equally spaced starts for the cutting tool within the circumference of the bore of the gun barrel to be rifled.

As shown by Figures 1 and 2, of the drawings, a rifling bar 35 is positioned within the bore of the gun barrel 28. This rifling bar is supported at its ends by the supports 36 and 37 straddling and fixed to the bed rails 2 and 3. As shown in Figures 3, 5 and 6, the rifling bar 35 is cylindrical in cross section and its profile conforms to the profile of the gun bore. That is to say, the profile of the rifling bar 35 is provided with a taper portion 38 to conform to the taper portion of the gun barrel. The diameters of the rifling bar throughout its length conform to the diameters of the bore with the exception that they are .001" to .002" under the bore size. The rifling bar does not, however, conform to the form and diameter of the firing chamber of the gun barrel and, therefore, the maximum diameter of the rifling bar should not be greater than .001" to .002" under the diameter of the major diameter of the gun bore. The rifling bar 35 is provided with a spiral groove 39 of uniform depth. Said spiral groove is geometrically designed to correspond to the rifling groove to be produced in the gun bore and to have the required number of turns.

In order to accurately position the rifling bar 35 within the gun barrel 28, so that the taper of the rifling bar will correspond and be exactly correlated to the taper in the bore, the following described mechanism shown in Figures 1, 3 and 13 of the drawings is provided. The support 36 in which the breech end of the rifling bar 35 is secured as through a locating pin 350 (Figure 14) and, if desired, by a hinged clamping cap 351, is clamped to the breech end of the gun barrel by means of the clamp ring 40. The clamp ring 40 is bolted to the support 36 by bolts 360 which engage a ring 41 having a hub 410 journaled with respect to the support 36 and the bolts may be adjusted to change the position of the support 36 longitudinally of the bed 1 to relatively position the rifling bar 35 longitudinally of the gun barrel 28 and thus accurately aline the taper portion 38 of the rifle bar with the taper portion of the gun barrel.

The apparatus as just described provides for the support of a gun barrel 28 with a rifling bar 35 accurately positioned within its bore to conform to ".001" to ".002" under bore size. The cable 15 is passed through the spiral groove 39 of the rifling bar 35 and is connected to a cutter or broach assembly slidably positioned within the spiral groove. This cutter or broach assembly will be described in detail hereinafter. When the cable 15 is moved in response to the reciprocation of the cable carriage 17 and piston rod 7, the cutter or broach assembly will be moved in a spiral path as defined by the spiral groove 39. By adjusting the cutter to a cutting relation with the bore, a rifle groove will be produced in the gun bore as the broach assembly is pulled through the spiral groove of the rifling bar in response to the movement of the cable or other flexible wire-like element.

The mechanism for adjusting the cutter or broach assembly into and out of cutting relation with the bore of the gun barrel will now be described, together with details of the broach assembly.

Referring to Figures 7 to 12, inclusive, a single cutter broach assembly is shown. Slidably positioned within the spiral groove 39 of the rifling bar 35, the broach assembly is comprised of the tool carrier 42 and the cutting tool 43. The tool carrier 42 is of approximately rectangular shape with the exception that its vertically extending longitudinal sides are shaped to conform to the shape of the walls of the spiral groove 39 thus enabling the tool carrier 42 to be freely slidable in said spiral groove. The tool carrier 42 is bored to receive a tool adjusting rod 44 which may be moved within predetermined limits relative to the tool carrier 42. The adjusting rod 44 is provided with the cam surface or incline 45 which engages the cutter 43 mounted for longitudinal adjustment in a slot 452 through the tool carrier 42, and advances the cutter in and out of the broach assembly in response to the relative movement of said adjusting rod and tool carrier. The tool adjusting rod 44 is connected with the cable 15 by any suitable threaded couplings such as 46 and 47.

The relative movement of the tool carrier 42 and tool adjusting rod 44 is confined to predetermined limits by the stops or spacers 48 and 49 which are threaded to the tool adjusting rod. The adjusting rod 44 is also limited in its movement to the left relative to the tool carrier 42 to thus effect a withdrawing of the cutting tool 43 from a cutting relation by the shoulder 50 abutting the adjusting nut 51. A slot 75 in the tool adjusting bar 44 permits

the removal of the cutting tool 43 for regrinding when the bar 44 is moved to the extreme left position relative to the tool carrier 42 as shown in Figures 9 and 11, permitting a hooked extremity 451 of the tool which normally rides beneath the rod 44 as shown in Figure 10 to pass the rod 44 as shown in Figure 11. To limit the relative movement of the tool adjusting bar 44 to the right to thus effect a cutting relation of the cutter 43 and determine the maximum depth of cut, the shoulder 52 is provided to abut the adjusting nut 53. Springs 54 are positioned as shown engaging friction plugs 540, which, in turn, engage the inner face of the nut 53 to maintain the adjusting nuts 51 and 53 in their adjusted positions. The adjusting nuts 51 and 53 are provided with splines 55 and 56 which may cooperate with the splines of a manually operated tool adjusting mechanism to be later described. Figure 7 shows the tool adjusting rod 44 moved to the right relative to the tool carrier 42 within the limit established by the position of the tool adjusting nut 53 and shoulder 52 for extreme depth of cut on the cutting stroke, while Figure 8 shows the tool retracted for the return stroke, the nut 51 engaging the stop shoulder 50. By further retraction of the nut 51, the rod 44 may be given sufficient amplitude to present the cut out 75 into registry with the tool for removal of the tool as shown in Figures 9 and 11.

Figure 17 of the drawings is an enlarged sectional view of a broach assembly similar to that shown and described in connection with Figures 7 and 12, except that it is provided with two cutters 43a and 43b provided with oppositely faced cutting edges so that a groove may be cut in a bore by a passage of the broach assembly in either direction of its travel, both forward and reverse. The tool adjusting rod 59 within the tool carrier 60 is provided with the oppositely inclined cam surfaces 61 and 62 so that a relative movement of the adjusting rod 59 to the tool carrier 60 will effect a withdrawal from cutting relation of one cutting tool and an application of the other cutting tool into cutting relation with the surface to be cut. This double cutter broach assembly is provided with the same stops, adjustments, and manual cutter adjusting mechanism as described in connection with the assembly shown in Figures 7 to 12 and therefore their descriptions will not be repeated.

In order to provide for a manual adjustment of the cutter in the broach assembly during the operation of the machine and to indicate the depth of successive cuts, the apparatus shown in detail by Figures 13 and 19 may be employed. Bolted to the end of the rifling bar 36 is the broach or cutter adjusting bracket 63. Rotatively journaled within said bracket is the sleeve 64 having splines 65 adapted to engage the splines 55 of the cutter adjusting nut 53. Keyed to the sleeve 64 is the two-part hand wheel 66, one part having a series of graduations 67 to indicate the amount of rotation of the sleeve 64 and adjusting nut 53 and, therefore, the relative position of the adjusting rod 44 and the depth of cut for the cutter 43. The other part of the hand wheel carries suitable actuating handles. The cable 15 passes through the cable bushing 68 secured to the sleeve 64 by the cap 69.

In operating my rifling machine as described in connection with the cutter or broach assembly of my invention, the adjusting nut 51 is adjusted so that the cutter 43 will not engage the surface of the bore in the gun barrel when the cable 15 and the tool adjusting rod 44 are moved to the

left relative to the tool carrier 42. The piston rod 7 is then actuated to move the cable carriage to the left and, therefore, move the broach assembly to the left through the spiral groove 39 of the rifling bar from the muzzle to the breech end of the gun barrel. Splines 55 of the adjusting nut will then be engaged with the splines 65 of the cutter adjusting sleeve 64. The hand wheel 66 is then turned to rotate the adjusting nut 53 and provide for a limitation of the movement of the tool adjusting rod 44 to the right relative to the tool carrier 42 to thus effect the desired depth of cut by the cutter 43. Upon the movement of the cable carriage 17 and cable 15 to the right in response to motion of the piston rod 7, the tool adjusting rod 44 will be moved to effect a movement of the cutter 43 into cutting relation as determined by the setting of the adjusting nut 53. Thus the broach assembly will be moved through the bore with the cutter in a cutting relation to produce a spiral groove in the bore conforming to the groove in the rifling bar. Upon again reversing the direction of travel of the cable carriage 17, adjusting rod 44 will be moved to the left until the shoulder 50 abuts the adjusting nut 51, withdrawing the cutter 43 from a cutting relation with the bore and then the broaching assembly is drawn back. After the broach has returned to the breech end of the barrel, the hand wheel 66 may be readjusted to provide for an increase in depth of cut, and the cycle of operation may be repeated until the desired depth of rifle groove in the bore is obtained. Thereupon the gun barrel may be manually rotated and indexed to new stations as provided by the index plate 29 previously described and the cycle of operation in cutting a new rifle groove may be repeated until all the desired rifle grooves in the barrel are produced.

Instead of operating the machine as just described, an alternate procedure as follows may be employed:

After the broaching assembly has made one complete cut through the barrel and has been returned to its starting position, the index locking lever 31 may be manipulated and the barrel manually rotated to the next index station on the index plate 29 and there locked. Thereupon the broach assembly may be moved through the barrel in cutting relation giving exactly the same depth of cut as previously cut, since the cutter adjusting mechanism has not been changed. After each cutting cycle, the barrel is indexed to the next station until all of the rifling grooves have been cut to the depth provided for by the cutter adjustment. Thereafter, the cutter adjustment may be changed to give increased depth of cut and the broach assembly passed through the bore in cutting relation for each of the grooves as provided for by indexing the barrel. This cycle of operation is continued until all of the rifle grooves are produced to the required depth.

Control handles 70 and 71 in connection with the control rod 72 and limit switches, one of which is shown at 73, control the reciprocating movement of the cable carriage 17 and piston rod 7 as is general practice in the machine tool art.

In some cases it may be found desirable to employ means for holding the broach assembly against the base of the spiral groove 39 while it is being traversed and means for so doing adjacent to both ends of the broach assembly have been illustrated in the drawings. Such means comprises a plate 700 extending across a trans-

verse groove 710 in the outer face of the tool carrier 42, and having end flanges 720 and 730 riding beneath overlying flanges 740 and 750. The outer top face of the plate 700 is beveled as at 76 to facilitate insertion of the tool carrier in the bore of the groove. This plate 700 is pressed outwardly as by springs 78 positioned in sockets in its inner face and bearing against the base of the carrier slot 710 so as to bring its outer beveled edges 790 into bearing contact with the interior face of the gun barrel bore as shown in Figure 18. The overlying carrier flanges 740 and 750 prevent disassembly of the plate when the broach assembly is outside of the gun barrel bore.

When the double cutter broach assembly described in Figure 17 is employed, it should be noted that the movement of the cutters into and out of cutting relation with the bore will be controlled by the direction of travel of the broach assembly through the bore. Because of the oppositely inclined cam surfaces for moving the cutters, only the designated cutter for the particular direction of travel of the broach assembly will be maintained in a cutting relation with the bore. The adjustments and stops for controlling the depth of cut are the same as described in connection with a single cutter broach assembly, except that an additional manual cutter adjustment assembly (not shown), which may comprise a hand wheel and cutter adjusting sleeve similar to that shown in Figure 13, may be provided on the rifling bar support 37 at the muzzle end of the gun barrel to enable an adjustment and indication of the depth of cut produced during its cutting stroke by the cutter 58. It should be obvious that when the double cutter broach assembly is used it is not necessary to adjust the broach assembly to a non-cutting relation and return it to the starting point in the bore before making the next cut since the double cutter broach assembly will make a cut in each direction.

I have described in connection with my invention, a rifling bar having a rifling groove of uniform depth extending from the surface of the rifling bar whose profile corresponds to the profile of the bore of a taper bore gun or the like. Thus a desired cutting relation is maintained throughout the passage of the broach assembly 50 in the rifling groove of the rifling bar. If rifling grooves of varying depth are desired to be produced in the gun bore, a variation in depth of the groove in the rifling bar may be employed to obtain this desired cutting relation, and it may also be advantageous under certain circumstances, as when the profile of the rifling bar departs somewhat from the bore of the gun barrel, to vary the depth of the spiral or helical groove in the rifling bar along the length of the helix 60 to obtain either a uniform or a non-uniform depth of cutting or rifling in the bore surface of the gun barrel, as may be desired.

While I have described the rifling machine of my invention in connection with the rifling of a taper bore gun, it should be understood that my method and apparatus may be employed to rifle the standard form of straight bore gun barrels by modifying the profile of the rifling bar to correspond to the profile of the straight bore.

I have shown and described above, a new method and apparatus for rifling the bore of gun barrels and what I claim as new and desire to secure by Letters Patent is:

1. Apparatus for rifling a gun barrel having a bore of varying diameter comprising an elongated

bed, means to support a gun barrel in a stationary position longitudinally over said bed, means associated with said gun barrel supporting means to permit rotation and indexing of the gun barrel to a plurality of radially spaced stationary positions, means constituting a rifling bar adapted to extend through the bore of said barrel and be supported at each of its ends on the elongated bed, said rifling bar having a profile corresponding to the profile of the gun bore, a spiral groove of predetermined lead and uniform depth on said rifling bar, an adjustable broaching assembly slidably positioned in said spiral groove, manual adjusting means associated with an end of said rifling bar to permit a manual adjustment of said adjustable broach assembly when in position at the end of said spiral groove, and flexible means associated with said spiral groove and broaching assembly to reciprocate said broaching assembly within the spiral groove extending through the gun bore.

2. Apparatus for rifling a gun barrel having a bore of varying diameter comprising an elongated bed, means to support a gun barrel in a stationary position longitudinally over said bed, means associated with said gun barrel supporting means to permit rotation and indexing of the gun barrel to a plurality of radially spaced stationary positions, means constituting a rifling bar having a profile corresponding to the profile of the gun bore and adapted to extend through the bore of said barrel and be supported at each of its ends on the elongated bed, means to longitudinally position said rifling bar relative to the barrel and thereby relatively position the profile of said rifling bar with the profile of the gun bore, said rifling bar having a spiral groove of predetermined lead and uniform depth in its surface, an adjustable broaching assembly slidably positioned in said spiral groove, manual adjusting means associated with an end of said rifling bar to permit a manual adjustment of said adjustable broach assembly when in position at the end of said spiral groove, and flexible means associated with said spiral groove and broaching assembly to reciprocate said broaching assembly within the spiral groove extending through the gun bore.

3. Apparatus described in claim 1 wherein said manual adjusting means comprises a rifling bar support, a sleeve rotatably journaled on said support, a hand wheel keyed to one end of said sleeve, splines extending from the other end of said sleeve, said splines adapted to engage and cooperate with the adjusting means of said adjustable broach assembly when said broach assembly is in position at the end of said spiral groove, whereby an adjustment of the broach assembly may be made by a rotation of said hand wheel.

4. An adjustable rifling broach comprising a tool carrier, a cutting tool carried by said tool carrier and adapted to be moved into and out of a cutting relation, a tool adjusting rod passing through said tool carrier and adapted to be moved relative to and longitudinally of said tool carrier, a cam surface on said tool adjusting rod, said cam surface engaging said cutting tool and adapted to move said cutting tool in response to the relative movement of the tool adjusting rod and tool carrier, and adjustable means to limit the relative movement in either direction of said tool adjusting rod.

5. An adjustable rifling broach comprising a tool carrier, a pair of cutting tools having oppo-

sitely faced cutting edges carried by said tool carrier and adapted to be moved into and out of a cutting relation, a tool adjusting rod passing through said tool carrier and adapted to be moved relative to and longitudinally of said tool carrier, a pair of oppositely faced cam surfaces on said tool adjusting rod, said cam surfaces engaging said cutting tools and adapted to move said cutting tools in response to the relative movement of the tool adjusting rod and tool carrier, and adjustable means to limit the relative movement in either direction of said tool adjusting rod.

6. Apparatus for producing a rifle groove in a gun barrel comprising means to support a gun barrel in position to be rifled, means adapted to extend through the bore of said gun barrel and support a broaching assembly for movement in either direction through the gun bore in desired relation to the bore, a broaching assembly movably positioned on said supporting means and including a cutter element, said broaching assembly provided with means for moving the cutter into and out of cutting relation with said bore, and flexible means connected to said cutter moving means and adapted to move the broaching assembly in either direction through the bore whereby the movement of the cutter will be controlled by the direction of travel.

7. Apparatus for producing a rifle groove in a gun barrel comprising means to support a gun barrel in position to be rifled, means adapted to extend through the bore of said gun barrel and support a broaching assembly for movement in either direction through the gun bore in desired relation to the bore, a broaching assembly movably positioned on said supporting means, a pair of cutting elements in said broaching assembly, one of said cutting elements adapted to be operative during movement of said broaching assembly in one direction through the bore and the other of said cutting elements adapted to be operative during movement of the broaching assembly in the other direction through the bore, a single cutter moving means for both of said cutting elements and adapted to selectively move one or the other of said cutting elements into cutting relation, and flexible means connected to said cutter moving means and adapted to move the broaching assembly in either direction through the bore whereby the direction of travel will control the cutting relation for each of the cutting elements.

8. Apparatus for rifling a gun barrel having a bore of varying diameter, comprising an elongated bed, means to support a gun barrel in a stationary position longitudinally over said bed, means associated with said gun barrel supporting means to permit rotation and indexing of the gun barrel to a plurality of angularly spaced stationary positions, means constituting a rifling bar adapted to extend through the bore of said barrel and be supported at each of its ends on the elongated bed, said rifling bar having a profile corresponding to the profile of the gun bore, a spiral groove of predetermined lead and depth in said rifling bar, an adjustable broaching assembly slidably positioned in said spiral groove, and flexible means associated with said spiral groove and broaching assembly to reciprocate said broaching assembly within the spiral groove extending through the gun bore, said gun barrel supporting means comprising a pair of heads spaced from one another mounted on said bed, gun barrel receiving spindles rotatively journaled in said heads, gun barrel chucking means fastened to said spin-

dles, and means associated with at least one of said heads to prevent rotation of its gun barrel spindle at predetermined angularly spaced points.

9. Apparatus for rifling a gun barrel having a bore of varying diameter, comprising an elongated bed, means to support a gun barrel in a stationary position longitudinally over said bed, means associated with said gun barrel supporting means to permit rotation and indexing of the gun barrel to a plurality of angularly spaced stationary positions, means constituting a rifling bar adapted to extend through the bore of said barrel and be supported at each of its ends on the elongated bed, said rifling bar having a profile corresponding to the profile of the gun bore, a spiral groove of predetermined lead and depth in said rifling bar, an adjustable broaching assembly slidably positioned in said spiral groove, and flexible means associated with said spiral groove and broaching assembly to reciprocate said broaching assembly within the spiral groove extending through the gun bore, said flexible means comprising a cable movable in said spiral groove and connected to said broach assembly, a cable carriage slidably mounted on said elongated bed and connected to said cable, and means for reciprocating said cable carriage.

10. Apparatus for rifling a gun barrel having a bore of varying diameter, comprising an elongated bed, means to support a gun barrel in a stationary position longitudinally over said bed, means associated with said gun barrel supporting means to permit rotation and indexing of the gun barrel to a plurality of angularly spaced stationary positions, means constituting a rifling bar having a profile corresponding to the profile of the gun bore and adapted to extend through the bore of said barrel and be supported at each of its ends on the elongated bed, means to longitudinally position said rifling bar relative to the barrel and thereby relatively position the profile of said rifling bar with the profile of the gun bore, a spiral groove of predetermined lead and depth in said rifling bar, an adjustable broaching assembly slidably positioned in said spiral groove, and flexible means associated with said spiral groove and broaching assembly to reciprocate said broaching assembly within the spiral groove extending through the gun bore, said longitudinal positioning means for said rifling bar comprising a rifling bar support movably positioned on said elongated bed, a ring clamp adapted to be clamped to the breech end of the gun barrel, and means to fasten said ring clamp to said rifling bar support.

11. Apparatus for rifling a gun barrel having a bore of varying diameter, comprising an elongated bed, means to support a gun barrel in a stationary position longitudinally over said bed, means associated with said gun barrel supporting means to permit rotation and indexing of the gun barrel to a plurality of angularly spaced stationary positions, means constituting a rifling bar adapted to extend through the bore of said barrel and be supported at each of its ends on the elongated bed, said rifling bar having a profile corresponding to the profile of the gun bore, a spiral

groove of predetermined lead and depth in said rifling bar, an adjustable broaching assembly slidably positioned in said spiral groove, and flexible means associated with said spiral groove and broaching assembly to reciprocate said broaching assembly within the spiral groove extending through the gun bore, said broach assembly comprising a tool carrier adapted to be slidably positioned in said spiral groove, a cutting tool

10 mounted in said tool carrier and movable into and out of cutting relation to the gun bore, a tool adjusting rod passing through said tool carrier and movable relative to said tool carrier, said tool adjusting rod having an inclined surface adapted 15 to engage said cutting tool whereby a relative movement of said tool adjusting rod and tool carrier will effect a movement of said cutting tool, and adjustable stop means for limiting the relative movement of said tool adjusting rod and tool carrier.

12. Apparatus for rifling a gun barrel having a bore of varying diameter, comprising an elongated bed, means to support a gun barrel in a stationary position longitudinally over said bed, means associated with said gun barrel supporting means to permit rotation and indexing of the gun barrel to a plurality of angularly spaced stationary positions, means constituting a rifling bar adapted to extend through the bore of said barrel and be supported at each of its ends on the elongated bed, said rifling bar having a profile corresponding to the profile of the gun bore, a spiral groove of predetermined lead and depth in said rifling bar, an adjustable broaching assembly slidably positioned in said spiral groove, and flexible means associated with said spiral groove and broaching assembly to reciprocate said broaching assembly within the spiral groove extending through the gun bore, said adjustable broach assembly comprising a tool carrier adapted to be slidably positioned in said spiral groove, a pair of cutting tools having oppositely faced cutting edges mounted in said tool carrier and movable into and out of cutting relation to the gun bore, a tool adjusting rod passing through said tool carrier, said tool adjusting rod having a pair of oppositely inclined surfaces, one of each inclined surfaces adapted to engage one of each cutting tools, whereby a relative movement of said tool adjusting rod and tool carrier will effect a corresponding movement of said cutting tools, and adjustable stop means for limiting the relative movement of said tool adjusting rod and tool carrier.

JOHN E. LOVELY.
